United States Patent Office

Des. 222,540
Patented Nov. 2, 1971

222,540

FOOT VALVE

John F. Campbell, Fergus, Ontario, Canada, assignor to
GSW Limited—GSW Limitee, Toronto, Ontario, Canada

Filed June 8, 1970, Ser. No. 23,361

Term of patent 14 years

Int. Cl. D23—01

U.S. Cl. D23—19

FIG. 1

FIG. 2

FIG. 3

FIG. 1 is a perspective view of a foot valve embodying my new design;

FIG. 2 is a side elevation view thereof; and

FIG. 3 is a top plan view thereof.

I claim:

The ornamental design for a foot valve, as shown.
